BRIDGE-STOP FOR SLIDE FASTENERS OR
THE LIKE

William A. Erhardt, Jr., Philadelphia, Pa.

Application August 7, 1947, Serial No. 767,125

1 Claim. (Cl. 24—205.11)

1

The present invention relates to bridge-stops for slide-fasteners or the like and it relates more particularly to a new and improved bridge-stop construction which will more effectively maintain the flexible slide-fastener beads in spaced-apart relationship at the side which carries the fastener elements while bringing the bridges into contiguous relationship at the other side.

An object of the present invention is to provide a new and improved construction for bridge-stops for slide-fasteners. Another object of the present invention is to provide a slide-fastener bridge-stop which is simple and inexpensive to manufacture and install and which is sturdy and dependable and which, at the same time, will effect a neat closure for the slide-fastener.

Other objects and advantages of the present invention are apparent in the following detailed description, appended claim and accompanying drawings.

It has been suggested in the past to provide bridge-stops for slide-fasteners for the purpose of maintaining the beads in spaced-apart relationship at the side which carries the fastener elements (in order to permit the slider to work freely to the end of the fastener) and, at the same time, to bring the beads closer together on the other side of the stop to make a neater appearance. Thus, Norton Patent 2,063,879 suggests the use of a generally enclosed curved tubular element having open ends into which the beads extend; the beads being enclosed within the tubular element and emerging therefrom in generally side-by-side relationship. Norkin 2,397,037 shows a slightly modified construction wherein the bridge-stop is more or less skeletonized so that only four pairs of curved tines extend from the sides of the bridging-portion and grip the beads so as to hold them against the curved bridging-portion.

However, these conventional constructions have certain disadvantages in that they are rather difficult to produce and install and, moreover, tend to fail or loosen during use.

According to the present invention, I provide a novel bridge-stop construction which effects a neat closure for the slide-fastener and which is simple and inexpensive to manufacture and install and which eliminates the shortcomings of the prior-art so as to provide a firm and dependable gripping action.

For the purpose of illustrating the invention, there is shown in the accompanying drawings one form thereof which is at present preferred, although it is to be understood that the various

2

instrumentalities of which the invention consists can be variously arranged and organized and that the invention is not limited to the precise arrangements and organizations of the instrumentalities as herein shown and described.

Referring to the accompanying drawings in which like reference characters indicate like parts throughout:

Figure 1 represents a plan view showing a "blank" stamped from sheet metal or the like as a preliminary stage in the form of the bridge-stop of the present invention.

Figure 2 represents a side elevational view of the "blank" of Figure 1.

Figure 3 represents a perspective view showing the bridge-stop as it appears when ready for installation on the slide-fastener beads; the "blank" of Figures 1 and 2 having been modified by curving up the intermediate bridging-portion and by bending the intermediate pairs of gripping tines or claws into partially closed relationship.

Figure 4 represents a front elevational view showing the novel bridge-stop of the present invention as it appears when installed upon the slide-fastener; the fastener-carrying beads being shown in open relationship.

Figure 5 represents a view generally like that of Figure 4 but showing the slide-fastener in fully-closed position.

In one embodiment of the present invention shown in Figures 1-5, I may provide a bridge-stop indicated generally by the reference character 10.

The bridge-stop may be integrally formed from sheet metal or the like by first stamping out a "blank," shown in Figures 1 and 2, which includes left and right wing portions 11 and 12 and an intermediate bridging-portion 13.

Left and right pairs of side members 14 and 15 respectively extend laterally from the bridging-portion 13.

Opposed gripping tines or claws 16 and 17 are formed at the ends of the left and right wings 11 and 12 respectively.

After the "blank" shown in Figures 1 and 2 is stamped out, it is bent into the form shown in Figure 3 by use of any conventional dies, in a manner well-known in the art. Thus, as shown in Figure 3, the bridging-portion 13 is curved upward relative to the wings 11 and 12, and the members 14 and 15 are curved toward each other so as to form opposed pairs of gripping tines or claws. The wings 11 and 12 (and the tines 16 and 17) still lie in generally the same plane while the tines 14 lie in a plane generally at 45° to the

wing 11 and the tines 15 lie in a plane generally at 45° to the wing 12; the planes of the pairs of tines 14 and 15 forming generally a right angle which is bisected by the center-line of the slide-fastener when the bridge-stop is installed in the manner shown in Figure 4.

In installing the bridge-stop 10 upon its slide-fastener, the left and right flexible beads 18 and 19, which carry the fastener elements 20, are positioned so that they overlie the curved bridging-portion 13; the bead 18 passing intermediate the tines 16 and the tines 14 while the bead 19 similarly passes intermediate the tines 17 and the tines 15.

The tines 14 and 15 and 16 and 17 are then clamped together by any suitable clamping tool or mechanism so as to cause them to hold the beads in immovable relationship to the bridge-stop. As can be seen in Figure 4, the fastener-element-carrying portions of the beads 18 and 19 are maintained in generally parallel spaced-apart relationship (with the tines 16 and 17 at right angles thereto). The beads extend across the curved bridging-portion 13 of the bridge-stop and emerge from the upper tines 14 and 15 at a converging angle of approximately 45° which tends to bring the beads together a short distance above the bridge-stop.

As indicated in Figure 5, the bridge-stop is effective in retaining the beads 18 and 19 in proper spaced relationship to permit the slider 21 to work easily right up to the bridge-stop.

It is evident that the tines 16 and 17 are not bent relative to the plane of the wings 11 and 12. I have found that this adds greatly to the strength of the bridge-stop and minimizes the possibility of failure. That is, in a construction of the type shown in Norkin Patent 2,397,037, the necessity for bending up the outer tines so that they form a relatively sharp angle relative to their base weakens them considerably so that they are apt to fail under the continued stress resulting from repeated opening and closing of the slide-fastener. In the novel construction of the present invention, on the other hand, these side tines 16 and 17 are not weakened by any severe bending operation and, therefore, are sufficiently strong to withstand all normal stresses.

It is also apparent that the novel bridge-stop of the present invention is much more easily

formed than the structures of the prior-art inasmuch as the "blank" requires only simple bending operation of the bridging-portion and of the upper ends of the tines 14 and 15, as compared to the more complex bending operations required by the prior-art structures.

The present invention may be embodied in other specific forms without departing from the spirit or essential attributes thereof, and it is therefore desired that the present embodiment be considered in all respects as illustrative and not restrictive, reference being had to the appended claim rather than to the foregoing description to indicate the scope of the invention.

Having thus described my invention, I claim as new and desire to protect by Letters Patent:

In a slide-fastener having a pair of flexible fastener-carrying beads, a bridge-stop integrally formed of sheet metal or the like, said bridge-stop having an uppermost central downwardly-bent bridging portion and having a wing-portion extending from each end of said bridging portion and reversely bent relative thereto so as to extend generally horizontally, the free end of each of said wing-portions being formed as a pair of opposed claws bent only in the plane of the wing-portion and constructed and arranged to grip the beads and to maintain them in generally vertical spaced-apart relationship, and pairs of upwardly-inclined curved claws integrally with and extending from the edges of said bridging-portion and constructed and arranged to grip the beads at points spaced upwardly and inwardly from the first-mentioned claws thereby to maintain said beads in upwardly converging relationship above said bridge-stop.
